UNITED STATES PATENT OFFICE.

JOSEPH L. WOODBRIDGE, OF PHILADELPHIA, PENNSYLVANIA.

RAILWAY SIGNAL SYSTEM.

Application filed November 3, 1921. Serial No. 512,525.

My invention relates to signal systems employing a track circuit consisting in part of the two opposite rails of a railway track, these rails constituting a section of the track 5 insulated at each end from the adjoining sections. A track circuit of this kind, which is used for conducting current for actuating relays or similar signal devices, is frequently subject to the interference of so-called foreign or stray currents, originating, for example, in the return circuit of a neighboring electric railway, where the track is used for the return conductor.

One object of my invention is to furnish 15 simple, reliable and inexpensive means for preventing such foreign currents from interfering with the operation of the signals and especially for preventing such foreign currents from giving a false "Clear" indication. Other objects of the invention will appear 20 from the following description, in which reference is made to the accompanying drawings forming part hereof and in which—

25 Figure 1 shows diagrammatically a portion of a railway signal system embodying features of my invention and employing a single auxiliary relay, and

Fig. 2 shows a modification of the system 30 shown in Figure 1 in which two auxiliary relays are employed.

In the drawings 1 and 2 are the opposite rails of a section of railroad track insulated from the adjoining sections at 32, 33, 34 35 and 35. The source of current 3 here shown as a battery is connected across the opposite rails at one end of the section with a limiting resistance 4 in series therewith. A relay 5 is located at the opposite end of the track section and is provided with an exciting coil 6 connected across the opposite rails, so that current from the source 3 passing over the rails 1, 2 and through the coil 6 will hold the relay in the closed position, thereby making electrical connection 40 between the contact points 7 and 8, and maintaining the continuity of the signal circuit 9, 10 at the relay 5. The signal circuit 9, 10 supplies current for operating signals 45 or signal relays, or similar devices well known in the art, but inasmuch as these devices form no part of the present invention, they are not here shown. The circuits and apparatus thus far described are well 50 known and in common use at the present time and are designed to operate as follows:

When a train is located on the block between the insulating points 32, 33 at one end, and 34, 35 at the other, the wheels and axles constitute a low resistance shunt across 60 the rails 1, 2, which reduces the voltage between the rails 1, 2 and diverts current from the coil 6 to such an extent that the relay 5 is permitted to open and the circuit is broken 65 between the contacts 7 and 8, and the current is interrupted in the signal circuit 9, 10. This interruption of current operates the signals to give a "Stop" or "Caution" indication, as the case may be. Similarly, if

70 there is a broken rail on either side of the track between the points of connection of the source 3 and the points where the coil 6 is connected, the current in the coil 6 will be interrupted and the signals will be set to give a "Stop" or "Caution" indication. It 75 sometimes occurs, however, that in the case of a broken rail or of a train on the block with a high resistance joint in the track between the train and the coil 6, that stray currents from the ground, with which the 80 rails may be in contact, will pass through the coil 6, and hold the relay closed, thus causing the signals to give a false "Clear" indication. In order to prevent this result,

85 I have shown in Figure 1, an auxiliary relay 11, whose contacts 14 and 15 are connected in the signal circuit 9, 10 in series with the contacts 7, 8 of the relay 5. The relay 11 is provided with two exciting coils 12 and 13, but is so designed that when the 90 current in these coils is below a certain minimum, the relay will remain closed and will have no effect on the operation of the signals controlled by the circuit 9, 10. When, however, either or both of the coils 95 12, 13 are carrying a sufficient current the circuit across the contacts 14, 15 will be opened, and the effect will be the same as if the contacts of the relay 5 were opened; that is, a "Stop" or "Caution" indication 100 will be given by the signals controlled by the circuit 9, 10. Coil 12 is connected across the opposite ends of rail 1 by means of conductor 18, while coil 13 is connected across the opposite ends of rail 2 by means 105 of conductor 19.

Under normal conditions, assuming the positive terminal of the source 3 to be connected to rail 1, the current from the source 3 will flow along rail 1 and through coil 6 110 and back through rail 2. This current will produce a small voltage drop in rail 1 and

a small proportion of the current will be diverted by way of conductor 18 through coil 12 in the direction of the arrow 16. Similarly a small voltage drop will be produced in rail 2 by the return current, causing a small flow of current through coil 13, via conductor 19 in the direction of the arrow 17. Coils 12 and 13 are so wound that these two currents when flowing in the direction shown by the arrows 16 and 17 will oppose each other and have no effect on the relay. This relay should be so adjusted by means of the adjustable spring 40 that it will not open under normal operating conditions.

15 The effect of foreign currents traversing the rails will also be to produce a voltage drop between the two ends of the rails 1 and 2, but this foreign current will generally flow in the same direction in both rails and 20 any portion of these currents which may be diverted through coils 12 and 13 will have cumulative effects in the two coils; but the adjustment of spring 40 should be such that so long as the resistance of the rails is about 25 normal the voltage drop across the coils 12 and 13 will not be sufficient to open the relay.

If, however, one or both of the rails should be broken and at such time there should be sufficient foreign current flowing through the coil 6 to hold relay 5 in the closed position, there will, nevertheless, be an abnormal difference in voltage between the opposite ends of the broken rail, producing an excessive flow of current in one or both of the coils 12 and 13, which will open the relay 11, thus interrupting the flow of current in the control circuit 9, 10 and giving a "Stop" indication, whereas without the action of the relay 11, a false "Clear" indication would result.

In Figure 2 is shown a modification of the apparatus shown in Figure 1, consisting in the use of two relays 20 and 21 in place of the single relay 11. Relay 20 is controlled by a coil 26 connected across the opposite ends of rail 1 and relay 21 is controlled by a coil 27 connected across the opposite ends of rail 2. The contacts 22 and 23 of relay 20, and the contacts 7 and 8 of relay 5, and the contacts 24 and 25 of the relay 21 are all connected in series in the circuit 9, 10. Thus, if this circuit is opened at any one of the three sets of contacts, the current will be interrupted and a "Stop" or "Caution" indication will be given. Under normal operating conditions the drop in voltage between the opposite ends of rail 1 will not be sufficient to open relay 20 and the drop in voltage between the opposite ends of rail 2 will not be sufficient to open relay 21. However, if there is a break in rail 1 or rail 2, and if at the same time there is sufficient foreign current passing through coil 6 to hold relay 5 in a closed position, there will

be an abnormal difference in voltage between the opposite ends of rail 1 or rail 2, which will open relay 20 or relay 21, and give a "Stop" indication where otherwise a false "Clear" indication would have been given.

I claim:

1. In a railway signal system, the combination of a signal operating circuit, and a track circuit comprising the two opposite rails of a track section having a source of electric current connected across said rails at one point and a relay having its actuating coil connected across said rails at another point and having its contacts connected into the signal operating circuit, and an auxiliary relay provided with an actuating coil connected between two separated points of one of the rails and having its contacts connected in series with the contacts of the first mentioned relay in the signal operating circuit.

2. In a railway signal system, the combination of a signal operating circuit and a track circuit comprising the two opposite rails of a track section having a source of electric current connected across said rails at one point and a relay having its actuating coil connected across said rails at another point and having its contacts connected into the signal operating circuit, and an auxiliary relay having its contacts connected in series with the contacts of the first mentioned relay in the signal operating circuit, said auxiliary relay having an actuating coil connected between two separated points of one of the rails and adapted to open the circuit at the relay contacts with abnormal voltage across said actuating coil.

3. In a railway signal system, the combination of a signal operating circuit and a track circuit comprising the two opposite rails of a track section having a source of electric current connected across said rails at one point and having a relay with its actuating coil connected across said rails at another point and its contacts connected into the signal operating circuit, and two auxiliary relays having their contacts connected in series with each other and with the contacts of the first mentioned relay in the signal operating circuit, and whereof one relay is provided with an actuating coil connected between two separated points of one of the rails and the other is provided with an actuating coil connected between two separated points of the opposite rail, each of said actuating coils of the auxiliary relays being adapted to open the corresponding relay contacts with abnormal voltage across the coil.

4. In a railway signal system, the combination of a signal operating circuit, a track circuit comprising the two opposite rails of a track section having a source of

electric current connected across said rails at one point and a relay with its actuating coil connected across said rails at another point and its contacts connected into the signal operating circuit, and auxiliary controlling means for said signal operating circuit said means responsive to abnormal difference of voltage between separated points in either rail.

5. In a railway signal system, the combination of a signal operating circuit, and a track circuit comprising the two opposite rails of a track section having a source of

electric current connected across said rails at one point and a relay with its actuating coil connected across said rails at another point and its contacts connected into the signal operating circuit, and auxiliary means adapted to open said signal operating circuit, said means provided with two actuating coils, whereof one is connected between separated points of one of said rails and the other is connected across separated points of the other rail.

JOSEPH L. WOODBRIDGE.
